CONVERTIBLE OTTOMAN OR SIMILAR
ARTICLEPoul Frederik Wiberg Jörgensen,
Esbjerg, DenmarkApplication March 4, 1953, Serial No. 23,884
In Denmark June 20, 1950

Term of patent 14 years

(Cl. D15—1)

To all whom it may concern:

Be it known that I, Poul Frederik Wiberg Jörgensen, a subject of the King of Denmark, residing at the city of Esbjerg, Kingdom of Denmark, have invented a new, original, and ornamental Design for a Convertible Ottoman or Similar Article, of which the following is a specification, reference being had to the accompanying drawing, forming a part hereof, wherein:

Fig. 1 is a perspective view of a convertible ottoman or similar article, showing my new design, illustrated in closed bed-concealing position;

Fig. 2 is an end elevational view thereof showing the back-rest tilted forward and downward;

Fig. 3 is a perspective view, similar to Fig. 1, but showing the back-rest pushed rearward from the position of Fig. 2 and partially opened;

Fig. 4 is a perspective view similar to Fig. 3, but showing the back-rest unfolded over the seat; and

Fig. 5 is a perspective view, similar to Fig. 4, showing the article in completely open, bed-converted position.

I claim:

The ornamental design for a convertible ottoman or similar article, substantially as shown.

POUL FREDERIK WIBERG JÖRGENSEN.
